US00D996449S

(12) **United States Design Patent** (10) **Patent No.:** **US D996,449 S**
Seo et al. (45) **Date of Patent:** **** Aug. 22, 2023**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Kuonyoung Seo**, Suwon-si (KR); **Miyeon Park**, Suwon-si (KR)

(73) Assignee: **Samsung Electronics Co., Ltd.**, Suwon-si (KR)

(**) Term: **15 Years**

(21) Appl. No.: **29/785,759**

(22) Filed: **May 27, 2021**

(30) **Foreign Application Priority Data**

Dec. 24, 2020 (KR) 30-2020-0064999
 Dec. 24, 2020 (KR) 30-2020-0065003

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The outermost broken lines in the figures show a display screen or portion thereof and form no part of the claimed design. The remaining broken lines in the figures depict portions of the graphical user interface which form no part of the claimed design.

1 Claim, 1 Drawing Sheet
